(57) **CLAIM**

The ornamental design for a guard rail, as shown and described.

DESCRIPTION

FIG. 1 is a front perspective view of a guard rail, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a rear perspective view of the guard rail, illustrated with brackets that are adapted to be hung on a wall.

The broken line showing of mounting brackets is for the purpose of illustrating portions of the guard rail that form no part of the claimed design.
